(57) **CLAIM**

The ornamental design for a liquid beverage container, as shown and described.

DESCRIPTION

FIG. 1 is a front elevational view of the liquid beverage container of the invention;

FIG. 2 is a left side elevational view of the container;

FIG. 3 is a bottom view of the container;

FIG. 4 is a top view of the container;

FIG. 5 is a perspective view of the container; and,

FIG. 6 is a perspective view of two stacked liquid beverage containers, each showing my new design, with the additional liquid beverage container being shown in broken lines for illustrative purposes only since the stack itself forms no part of the claimed design.

The liquid beverage container of the invention is formed from transparent material.
